BRASSIÈRE

Henrietta Grein, Cheney, Wash.

Application August 18, 1936, Serial No. 96,658

5 Claims. (Cl. 2—42)

This invention relates to apparel and more particularly to a brassière, one object of the invention being to provide a brassière of such construction that it may be adjusted and caused to fit properly when worn and conform to the size of the wearer.

Another object of the invention is to so construct the brassière that a strap of tape or ribbon which extends about the lower edge portion of the brassière may have one end adjustably secured at the back of the brassière and the other end portion of the strap brought forwardly to the front where it can be very easily secured in an adjusted position and thus cause the lower edge portion of the brassière to be properly constructed and held in place.

Another object of the invention is to provide an improved clip or coupling for slidably connecting portions of the strap at the back of the brassière and to also provide an improved fastener at the front of the brassière which is of such construction that a stud carrier may be shifted along a base plate of the fastener and secured in the proper position to hold the strap at the desired tightness when a socket carried by the strap is engaged with the stud.

Another object of the invention is to so form the base plate and the stud carrier that while the stud carrier may be easily slid from one position to another along the base plate, it will be firmly secured after being moved to the desired position of adjustment.

The invention is illustrated in the accompanying drawing, wherein

Figure 1 is a perspective view of the improved brassière.

Figure 2 is an enlarged view of the rear portion of the brassière.

Figure 3 is a fragmentary perspective view of the front portion of the brassière.

Figure 4 is a sectional view taken along the line 4—4 of Figure 3.

Figure 5 is a sectional view taken transversely through the front fastener along the line 5—5 of Figure 6.

Figure 6 is a perspective view of the front fastener.

The improved brassière has a body 1 formed of fabric having tapered end portions 2 and 3 which extend rearwardly about the wearer when the brassière is in use. The usual shoulder straps 4 extend upwardly from the end portions 2 and 3 and are secured at their front ends to the front of the brassière body. A strap 5 which is formed of ribbon or tape extends about the body 1 along the lower edge portion thereof where it is secured

by stitching, as shown at 6, but it should be noted that the end portions 2 and 3 of the body are free. One end portion of the strap 5 is folded back upon itself to provide a loop 7 which is engaged through one of the openings 8 in the plate or clip 9 and a snap fastener 10 is provided to secure this end portion of the strap in loop-forming formation. Therefore, the loop may be released and passed through any one of the openings 8 desired and adjustments thus accomplished. The other end portion of the strap is of greater length than the end portion forming the loop 7 and this end portion 11 is passed through an opening 8 at the opposite end of the plate 9 from the loop 7 and brought forwardly about the body of the brassière. This end portion of the strap is of such length that it will extend to the front of the brassière and at its free end carries a snap socket 12 which is sewed against the inner face of the strap.

The free end of the extension 11 is to be adjustably secured at the front of the brassière, and in order to do so there has been provided a front fastener having a base plate 13 which is secured against the strap 5 by stitches 14 at each end and extends longitudinally of the strap. Portions of the plate are stamped therefrom to provide bars 15 which extend longitudinally of the base plate near upper and lower edges thereof and are punched to form pins 16 which project rearwardly from the bars in spaced relation to each other longitudinally thereof. Since the plate 13 is formed of resilient metal, the bars may be sprung outwardly away from the same and then return to their normal positions. A stud 18 for engagement with the socket 12 has a base 19 formed with end extensions providing tongues 20 and this base is disposed transversely of the plate 13 so that the tongues 20 project under or back of the bars 15. Openings 21 are formed in the tongues to receive the pins 16 and it will be readily understood that when the pins 16 are engaged in the openings, the stud will be firmly held in an adjusted position longitudinally of the plate 13. By grasping the stud 18 and tilting the base 19 transversely, the bars 15 will be sprung forwardly a sufficient distance to move the pins 16 out of the openings of the tongues 20 and the stud may then be shifted longitudinally of the plate to a desired position and then released so that it returns to a position in which the base bears flat against the plate 13 and a pair of pins 16 engage through the openings of the tongue to secure the stud in the adjusted position.

When the brassière is in use, it is applied in

the usual manner with the straps 4 over a person's shoulders and the end portions 2 and 3 of the brassière at the back. The extension 11 of the strap 5 is passed through the end opening of the clip or plate 9 and brought forwardly to the front of the brassière where the socket 12 is engaged with the stud 18. If it is found that the brassière is too tight or too loose, it is merely necessary to release the socket from the 10 stud and after shifting the stud along the plate 13 again engage the socket with the stud. It will thus be seen that the brassière may be properly adjusted to fit the person wearing the same and that it may be adjusted to accommodate itself to a growing girl or to changes in 15 a woman's figure due to increased weight as she grows older. The fact that the end portions 2 and 3 of the body are free from the strap 5 permits them to fit comfortably and since the loop 20 7 is releasably secured by the snap fastener 10, it can be shifted from one opening of the plate 9 to another and thus cause the rear plate to be disposed directly back of the front plate and the stud 18.

Having thus described the invention, what is claimed as new is:

1. A brassière comprising a body adapted to be disposed about the wearer with its end portions at the back and spaced from each other, a strap extending along the lower edge portion of said body and secured thereto with end portions of the strap free from the body and extending therefrom, a rear connecting member having openings formed therein, one end portion of said strap being passed through an opening of said member and secured, the other end portion of the strap being passed through an opening of said member and of a length adapting it to be brought forwardly back upon itself to the front of the body, and means associated with the front of the body to adjustably secure the last mentioned end of the strap.

2. A brassière comprising a body adapted to be disposed about the wearer with its end portions at the back and spaced from each other, a strap extending along the lower edge portion of said body and secured thereto with end portions of the body free from the strap to provide flaps and portions of the strap extending from 50 rear ends of the body, a rear guide between ends of said body, one end portion of said strap being detachably connected with said guide and adjustable longitudinally thereof, the other end portion of the strap being slidably engaged with 55 said guide and being of a length adapting it to be brought forwardly back upon itself along the lower edge portion of the body to the front of the body, and means associated with the front of the body to releasably engage and adjustably 60 secure the last-mentioned end of said strap.

3. A brassière comprising a body adapted to be disposed about the wearer with its end portions at the back and spaced from each other, a strap extending along the lower edge portion 65 of said body and secured thereto with its end portions projecting from ends of the body, a rear connecting member, one end portion of said strap being connected with the connecting member and the other end portion of the strap being

slidably engaged with the connecting member and of a length adapting it to be brought forwardly back upon itself to the front of the body, and securing means for the last-mentioned end of said strap consisting of a backing plate secured at the front of the body longitudinally thereof, a fastener member carried by said backing plate and adjustable longitudinally thereof, and a companion fastener member carried by the end of the strap and releasably connected with the fastener member of the backing plate.

4. A brassière comprising a body adapted to be disposed about the wearer with its end portions at the back and spaced from each other, a strap extending along the lower edge portion of said body and secured thereto with its end portions projecting from ends of the body, a rear connecting member, one end portion of said strap being connected with the connecting member and the other end portion of the strap being slidably engaged with the connecting member and of a length adapting it to be brought forwardly back upon itself to the front of the body, and securing means for the last-mentioned end of said strap consisting of a back plate secured to said body at the front thereof and elongated horizontally, bars extending longitudinally of said plate, a fastener member having a base engaged back of said bars and slideable along the plate to adjusted positions, means for releasably securing the base in an adjusted position, and a companion fastener member carried by the last mentioned end of said strap engageable with the fastener member of the plate.

5. In a brassière, a body adapted to be disposed about the wearer with its end portions at the back and spaced from each other, a strap extending along the lower edge portion of said body and secured thereto with its end portions projecting from ends of the body, a rear connecting member, one end portion of said strap being connected with the connecting member and the other end portion of the strap being slidably engaged with the connecting member and of a length adapting it to be brought forwardly to the front of the body, and securing means for the last-mentioned end of said strap consisting of a back plate secured to said body at the front thereof and elongated horizontally, resilient bars extending longitudinally of said plate in vertical spaced relation to each other, pins carried by said bars and projecting rearwardly therefrom in spaced relation to each other longitudinally thereof, a fastener member having a base extending transversely of said plate with portions engaged back of said bars and formed with sockets to receive selected pins of the bars and releasably secure the fastener member in an adjusted position, said fastener member being adapted to be tilted transversely and tilt its base transversely to spring the bars forwardly to move the pins out of the sockets of the base whereby the fastener member may be moved longitudinally of the plate to an adjusted position, and a fastener member carried by the last-mentioned end of said strap for engaging the fastener member of the plate and secure the strap.

HENRIETTA GREIN.
